The ornamental design for an electronic device and packaging therefor, as shown and described.

DESCRIPTION

FIG. 1 is a top perspective view of an electronic device and packaging therefor showing our new design;
FIG. 2 is a bottom perspective view thereof;
FIG. 3 is a front view thereof, the rear view being a mirror image thereof;
FIG. 4 is a side view thereof, the other side view being a mirror image thereof;
FIG. 5 is a top view thereof;
FIG. 6 is a bottom view thereof;
FIG. 7 is another top perspective view thereof with the cover in an open position;

FIG. 8 is an exploded view of the electronic device and packaging therefor of FIG. 1;

FIG. 9 is a bottom perspective view of the electronic device and packaging therefor of FIG. 1 with the cover in an open position;

FIG. 10 is a front view thereof, the rear view being a mirror image thereof; and,

FIG. 11 is a side view thereof, the other side view being a mirror image thereof.

The shade lines in the Figures show transparency, and not surface ornamentation.

The broken lines show portions of the electronic device which form no part of the claimed design.
